UNITED STATES PATENT OFFICE.

GEORGE W. HULSHIZER, OF STEWARTSVILLE, NEW JERSEY, ASSIGNOR TO INGERSOLL-RAND COMPANY, OF JERSEY CITY, NEW JERSEY, A CORPORATION OF NEW JERSEY.

WATER-TUBE GUIDE.

Application filed September 30, 1924. Serial No. 740,700.

To all whom it may concern:

Be it known that I, GEORGE W. HULSHIZER, a citizen of the United States, and a resident of Stewartsville, county of Warren, and

5 State of New Jersey, have invented a certain Water-Tube Guide, of which the following is a specification, accompanied by drawings.

This invention relates to fluid actuated percussive machines, and more particularly 10 to rock drills of the hammer type which employ means for conducting cleansing liquid to a hollow drill steel for removing cuttings from a drill hole and allaying dust incident to drilling. The liquid conducting member 15 so employed is usually in the form of a tube supported at its rearward end and extending through a reciprocating element into a drill steel, thus leaving the forward end of the tube suspended throughout its length, and 20 subjecting it to severe strains and wear due to vibration of the drill. By arranging an additional support for the water tube near its forward end, thus eliminating vibration thereof, it has been found that the life of 25 the tube may be considerably lengthened.

In some rock drills two longitudinally arranged tubes are employed, one of which is adapted to convey water and the other a pressure fluid, usually air, the motive fluid 30 being employed to augment the water pressure. Although the tubes thus employed conduct their respective fluids directly from a source of supply to the drill steel, there is no assurance of their proper intermingling 35 at regular intervals, whereas, by using only one tube, fluid pressure may be provided through controlled leakage past the piston and associated parts, the leakage thus employed preferably being supplied directly 40 from a source of supply, thus causing water and air to intermix in suitable proportions for removing cuttings from the drill hole.

One object of this invention is to support 45 the water tube near its front end in a rock drill of the hammer type.

Further objects will hereinafter appear in the following description and the accompanying drawings illustrating the invention in one of its preferred forms.

50 Figure 1 is a longitudinal view partly in section of a hammer type rock drill equipped with a water tube guide in accordance with the practice of the invention.

55 Figure 2 taken on the line 2-2 of Figure 1 is a transverse sectional view of a hammer

type rock drill showing the water tube guide and adjacent parts, and

Figure 3 is a perspective view of the water tube guide.

Referring to the drawings, the invention 60 is shown embodied in a rock drill of the drifter type in which a back cylinder A, a front cylinder B, a front head C supported within the hollow bore of the front cylinder B and a back head D are secured in operative relation by the usual side bolts (not shown). A hollow drill steel E supported within the front head C is adapted to receive impact blows of a reciprocatory hammer piston F. 65

Distribution of the actuating fluid is in this instance controlled by means of the rearwardly reduced end G of the hammer piston F. A throttle valve H disposed within the cylinder A is adapted to control the 70 supply of actuating fluid, said throttle valve communicating with a supply pipe J through a passage K and with the distributing element through a port L. 75

In order to impart a rotary movement to the drill steel E, thus keeping it free within the drill hole, a train of interlocking elements is employed. To this end the piston F is shown in slidable engagement at its rearward end G with a rifle bar O, and in similar engagement at its forward end with a chuck P through the medium of a chuck nut Q. Disposed within the forward end of the front head C is a chuck jaw R, rotatively engaged with the chuck P by means 80 of clutch members S and T. The chuck jaw R in turn interlocking with wings U of the drill steel E by means of flat sides V in a recess W. Within the head X of the rifle bar O are arranged a plurality of pawls 85 adapted to engage a rotation ratchet Y. By arranging the rotative elements in this manner a rotary movement is imparted to the drill steel on the backward stroke of the hammer piston, thus using the energy of the 90 piston on its forward stroke for impact purposes only. 95

In accordance with the invention, a cylindrical guide Z is shown supporting the forward end of a water tube b. The bore c of the guide Z is substantially of the same diameter as the diameter of the enlarged portion d of the tube b. In order to provide 100 for the passage of motive fluid to the drill steel, a plurality of longitudinal holes e 110

are formed in the wall of the guide Z. The holes e are so disposed that one side cuts into the bore c as at e' and communicates with the drill steel E through the recess f and the passage g in the nose h of the hammer piston F.

In operation the end G of the piston F is in continuous contact with the motive fluid, air is therefore constantly leaking past the flutes j of the rifle bar O into the interior k of the piston F, irrespective of the position of the hammer piston, and as the piston F travels on the upward stroke air continues to flow through the piston to the drill steel until the point m of the bore g comes in contact with the enlarged portion d of the water tube b. Since the bore g is of substantially the same diameter as the enlarged portion d of the water tube b, a seal is effected and the flow of air to the drill steel is checked until the piston again reaches a point in its forward travel where the sealing contact between the bore g and the enlarged portion d of the tube b is removed. In this manner an intermittent flow of motive fluid is admitted to the drill steel where it will intermix with the cleansing fluid near the tapered end p of the tube b.

In some cases the water tube is supported only at its rearward end without additional support throughout its length, but when the rock drill is in operation, the vibration caused by the reciprocating elements imparts a whipping motion to the tube, thereby causing it to strike against the walls of the adjacent parts. This, in addition to stresses set up within the walls of the tube, often results in a comparatively short period of service for a tube thus secured.

In the present invention the guide Z dis-

posed within the bore q of the piston F and secured either by a press fit as shown, or by other well known means, is adapted to support the water tube b slidably near its forward end. By so doing injurious vibration of the tube b is eliminated and the tube is held in a concentric position at all times.

I claim:

1. In a fluid actuated rock drill, the combination of a cylinder with a back head, a water tube secured at one end within the back head and extending through the piston, a guide fitted into the piston to reciprocate therewith and embracing the water tube to prevent vibration of said tube, said guide having perforations throughout its length for admitting pressure fluid to a drill steel when the piston nears the end of its forward stroke.

2. In a fluid actuated rock drill, the combination of a cylinder with a back head, a reciprocatory hammer piston having a reduced bore in its forward end, a water tube supported at one end by the back head extending through the piston and having an enlarged portion to cooperate with the reduced bore in the piston for sealing the front end of the piston during the rearward stroke, a guide fitted into the piston and having a bore to slidably embrace the water tube for preventing vibration of said tube, said guide having longitudinal perforations communicating throughout their length with the bore in said guide for admitting pressure fluid to a drill steel when the piston nears the end of its forward stroke.

In testimony whereof I have signed this specification.

GEORGE W. HULSHIZER.
